UNITED STATES PATENT OFFICE.

ALPHONSE F. MONEUSE, OF NEW ROCHELLE, NEW YORK.

WATER-HEATER.

No. 928,063.

Specification of Letters Patent.

Patented July 13, 1909.

Application filed June 20, 1908. Serial No. 439,555.

To all whom it may concern:

Be it known that I, ALPHONSE F. MONEUSE, a citizen of the United States, residing at New Rochelle, in the county of West-
5 chester and State of New York, have invented certain new and useful Improvements in Water-Heaters, of which the following is a specification.

This invention relates to water heaters;
10 and it consists essentially of the novel arrangement and combination of the several parts, as will be hereinafter fully described, and briefly stated in the claims.

The prime object of the invention is to pro-
15 vide an efficient heater, of the type men-
tioned, over which the water from the main,
or water supply, will be caused to circulate
slowly, alternately in reverse direction,
around the entire surface of the heater, so
20 that by the time the outlet is reached the
water will have become sufficiently heated
for immediate use.

While my improved heater is adapted for
25 general use in heating water, I have shown it
in connection with a coffee urn, wherein by
means of certain connecting pipes, the heat-
ed water may be supplied directly to the per-
colator of a coffee urn.

In the drawings; Figure 1 illustrates a side
30 elevation of the heater attached to a coffee
urn; Fig. 2 is a central vertical section of the
same; Fig. 3, is an enlarged perspective view
of the heater removed from its casing; Fig. 4
is a section on line 9—9 of Fig. 2, and Fig. 5
35 is a perspective view of a modified form of
heater.

Referring to the drawings, the numeral 1
designates the urn which may be of any im-
proved construction, and which may have in
40 connection therewith, any suitable burner or
burners such as are commonly used for heat-
ing water in urns of this character. Secured
to the side of the urn by brackets 2, is a cylin-
45 drical casing 3, having a valve controlled
water inlet 4, at its lower end, and an outlet
pipe 4' at its upper end, the pipe 4' being of
special construction, as will be presently de-
scribed. Within the casing 3 I arrange what
50 I term the water heater 5. This consists of a
pipe 5' of a diameter slightly smaller than
the interior diameter of the casing. Around
this pipe and firmly attached thereto, I place
a retarding device 6, which consists of a plu-
rality of circular webs 7, one end of each web

being integral with a vertical piece 8 extend-
ing preferably throughout the entire length
of the pipe 5. The ends of these webs are
alternately attached to the piece 8 throughout
the entire length of the piece, so that be-
tween one end of the bottom web and the
lower end of the piece 8, a space 9 will be left
to permit the water to begin its circulation
and at the top of the pipe, a corresponding
opening 10 occurs which permits the water
after it has passed many times around the
pipe 5, to pass into the urn. By reference to
Fig. 3 it will be seen that the water in enter-
ing the casing 3 will pass upward through the
opening 9 around the pipe 5' through the cir-
cular passage formed by the web 11 until it
reaches the passage 12, when it will pass up
and again around the pipe until it reaches the
passage on the opposite side of the piece 8
and so on until it reaches the point of outlet
at the top of the casing. The upper end of
the pipe 5 is closed, with the exception that
a valve controlled steam inlet pipe 13 is let
into it. This pipe passes through the top of
the casing wherein it is suitably packed and
may lead to any source of steam supply. 80

The lower end of the pipe 5 has connected
with it a pipe 14, which passes through a
suitably packed opening in the bottom of the
casing. Connected with the pipe 14 is a coil
15 which is suitably supported in the bottom
85 of the urn below the receptacle or vessel 16,
which receptacle has connected with it in the
usual way, a pipe 17 having a faucet 18 there-
on through which the contents of said recep-
tacle is drawn off. The pipe 15 is provided
90 with a valve 19 through which the steam
may be exhausted.

The pipe 4' is formed with a depending
portion 20 to the lower end of which is at-
tached the pipe 21 having a faucet 22 at the
lower end thereof and through which hot
water may be drawn before it passes into the
urn. Connecting the pipe 21 and the outer
casing of the urn is a short valve controlled
pipe 23 which may be opened to permit the
100 water after it has been passed through the
heater to pass into the bottom of the urn,
around the vessel or receptacle 16, it being
understood that when the bottom of the urn
is being filled to the desired extent, the faucet
105 22 will be closed. The faucet 22 and valve in
the pipe 23 may be independently operated
as the exigencies of the case may require.

The inner receptacle of the urn is provided with the usual percolator 24 suitably supported near the top of the casing and opening into this percolator is a screened pipe 25 which is a continuation of the pipe 4.

In operation, cold water is let into the casing 3 through the valve controlled inlet 4, where it passes through the opening 9 which is formed between one of the web sections 10 and the inner surface of the casing 3 and passing onto the pipe 5', it will pass many times around said pipe until it reaches the top of the casing, passing out of the casing into the urn. The temperature of the steam within 15 the pipe 5 is such that by the time the water reaches the upper part of the casing, it will have reached boiling point or such temperature as may be desired. The web sections fit snugly against the inner surface of the 20 casing so that the water is compelled to follow the course defined by the webs.

Referring now to the modification shown in Fig. 5 of the drawings, the retarding device 26 is formed by two circumferential webs 27 25 and 28 to which are attached a number of strips 29. These strips are alternately connected to the top and bottom web and are of such length that spaces 30 are formed between the webs and the ends of the strips 30 through which the water may circulate circumferentially of the pipe 5'. The lower web 28 is cut away as indicated at 31 so that the water coming into the casing may pass longitudinally of the pipe between the strip 35 29 and strip 32, which strip 32 has its upper and lower ends connected with the web, so as to separate the inlet opening from the outlet. The upper web is cut away to form the outlet opening 33 which occurs between the strip 32 40 and the adjacent strip 29. The water entering the inlet 31 will pass upward over substantially the entire length of the pipe and will then pass for a short distance or for the width of the strips 29 circumferentially of the 45 pipe when it will pass downwardly and through the various passages 30, until it finally reaches the outlet when it may pass into the urn or be conducted elsewhere for use in a highly heated state.

50 Claims.

1. A water-heater, comprising a casing having a water-inlet and an outlet, heat-supplying means arranged within the casing, and a retarding-device situated between the 55 walls of the casing and the means for supplying heat, said retarding device being so constructed and arranged that the water will be

caused to flow alternately in reverse directions, circumferentially and longitudinally 60 of the heater.

2. A water-heater, comprising a casing provided with a water-inlet and an outlet, heat-supplying means, arranged within the casing, and a retarding device situated between the walls of the casing and the means 65 for supplying heat, said retarding device consisting of a vertical piece provided with a plurality of webs alternately arranged to form water-passages at opposite sides of the vertical piece.

3. A water-heater, comprising a casing provided with a water-inlet and an outlet, a steam-pipe arranged within the casing, a retarding-device formed of a vertical piece having a plurality of circumferentially-arranged webs, said device being situated between the walls of the casing and steam-pipe and having each alternate web abutting against the vertical piece, whereby passageways are formed between the ends of each 75 alternate web, so that the water will be caused to flow alternately in reverse direction.

4. A water-heater, comprising a casing having a water-inlet and an outlet, a hollow 80 body within the casing, means for supplying heat to said body, a retarding device fitting between the walls of the casing and the hollow body, said retarding device being composed of a vertical piece provided with a 85 plurality of webs alternately-arranged at opposite sides thereof, forming communicating water passages.

5. A water-heater, comprising a casing having a water-inlet and an outlet, heat- 90 supplying means arranged within the casing, and a retarding device fitting between the walls of the casing and the means for supplying heat, said retarding device being composed of a vertical piece having a plurality of 95 webs projecting circumferentially from one side of piece, and a plurality of similarly projecting webs alternately arranged at the opposite side thereof, whereby passageways will be formed to cause the water to flow 100 alternately from one side of the vertical piece to the other in reverse directions, and longitudinally thereof.

In testimony whereof I affix my signature in presence of two witnesses.

ALPHONSE F. MONEUSE.
